UNITED STATES PATENT OFFICE.

ISAAC BERNSTEIN, OF ALAMEDA, CALIFORNIA.

POCKET.

1,426,539.

Specification of Letters Patent. Patented Aug. 22, 1922.

Application filed September 10, 1919. Serial No. 322,970.

To all whom it may concern:

Be it known that I, ISAAC BERNSTEIN, a citizen of the United States, residing at Alameda, in the county of Alameda and State 5 of California, have invented certain new and useful Improvements in Pockets, of which the following is a specification.

My invention is a pocket, particularly applicable to overalls.

10 Referring to the annexed drawing, which forms a part of this specification:

Figure 1 is a front view of my pocket applied to the bib of a pair of overalls.

15 Figure 2 is a sectional view taken on line 2—2 of Fig. 1.

Figure 3 is a sectional view taken on line 3—3 of Fig. 1.

In the drawing 1 indicates the outer fabric wall of the pocket which may be square 20 and sewed to the bib 2 of a pair of overalls

by a row of stitching 3 along the edge of the fabric. The fabric 1 is stitched to the bib by horizontal rows of stitching 4 and 5 near its lower and upper edges inside the 25 stitching 3, and by vertical rows of stitching 6 and 7, the row 6 being near the left edge of the fabric and the row 7 being inwardly from the right edge of the fabric and forming a vertical pocket compartment 8. The 30 fabric 1 is stitched to the bib by an angular row of stitching 9 extending downwardly and inwardly from the upper part of the row of stitching 6. The fabric 1 is formed with a slit 10 extending at a distance inwardly from the stitching 6 downwardly 35 from the stitching 5 in a vertical direction to the lower end of the stitching 9. The fabric 1 is secured to the bib 2 by a row of stitching 11 extending horizontally from the slit 10 a short distance below the stitching 5 to the stitching 7, forming a horizontal pocket compartment 12. The fabric 1 is formed 40 with a horizontal slit 13 at the top of the pocket compartment 8, and with slits 14 and 45 15 successively below slit 13, which provide entrance to said pocket compartment at different heights. Three angular rows of stitching 16 extending from the stitching 7

to the stitching 4 secure the fabric 1 to the bib 2. A pocket compartment 17 is formed 50 by the stitching 4, 6, 9, 11, 7 and 16, to which entrance is provided by slit 10, which slit also provides entrance to pocket 12.

A watch may be carried in the pocket 17. The stitching 16 causes the watch to rest 55 under the lower end of the slit 10 and prevents the watch from falling out of the pocket through the slit. A pencil is ordinarily carried in the pocket compartment 8. If the pencil is long it is introduced into said 60 pocket compartment through slit 13; if short through slit 14; and if of intermediate length it is introduced through the slit 15. If the workman has to stoop forwardly he may carry his pencil in the pocket compartment 12 where the point of the pencil will 65 not be liable to be broken.

The fabric 1 has a slit 20 at the end of the pocket compartment 12 opposite slit 10 through which the pencil may also be inserted as well as through slit 10 so that the pencil 70 may be held firmly intermediate its ends in said compartment.

Having described my invention, I claim:

1. A pocket including a single piece of 75 fabric sewed to a garment and forming a main pocket compartment, a horizontal compartment and a vertical compartment, said piece of fabric being formed with a single slit providing entrance to both the main 80 compartment and the horizontal compartment, said piece of fabric having a plurality of slits forming entrances to said vertical compartment at different heights.

2. A pocket including a single piece of 85 fabric sewed to a garment and forming a main pocket compartment and a horizontal pocket compartment, said piece of fabric being slit to form an entrance to both pocket compartments and slit to form another entrance to said horizontal pocket compartment. 90

In testimony whereof I affix my signature.

ISAAC BERNSTEIN.
